(57) **CLAIM**

The ornamental design for a photofacial apparatus, as shown and described.

DESCRIPTION

FIG. 1 is a front elevational view of a photofacial apparatus showing my new design;

FIG. 2 is a rear elevational view thereof;

FIG. 3 is a left side elevational view thereof;

FIG. 4 is a right side elevational view thereof;

FIG. 5 is a top plan view thereof; and,

FIG. 6 is a perspective view thereof.

The dash-dot-dot-dash broken lines are included for the purpose of illustrating portions of the photofacial apparatus that form no part of the claimed design.
